UNITED STATES PATENT OFFICE.

GUSTAVE O. DEGENER, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,149,187.

Specification of Letters Patent. Patented Aug. 10, 1915.

Application filed July 22, 1911. Serial No. 639,679.

To all whom it may concern:

Be it known that I, GUSTAVE O. DEGENER, a citizen of the United States, residing in New York city, in the county of New York and State of New York, have invented certain new and useful Improvements in Combined Type-Writing and Computing Machines, of which the following is a specification.

This invention relates to the type of combined typewriting and computing machines in which a computing carriage is intermittently connected to the carriage of a typewriter, to travel therewith. A hook is connected to the computing carriage, and is adapted to engage any of a series of lugs placed upon the typewriter carriage, which is power-driven. Mechanism is provided for automatically disconnecting said hook from the lugs in succession at certain points in the travel of the typewriter and computing carriages. A machine of this type is illustrated in the pending application of Walter Wright, No. 574,813, filed August 1, 1910. The present invention relates to the hook used in this class of machines.

One object of the invention is to improve the means for automatically disconnecting the hook, so that such disconnection may be effected without consuming an undue portion of the carriage driving power. To this end I provide a lever carrying a roll or roller cam, which is engaged by the lug, which is on the typewriter carriage. The provision of the roller cam renders the releasing action very light or easy. This releasing lever extends to the hook and bears upon a roll which is carried on said hook. Hence at the hook-releasing operation, the entire function is performed through roller contacts, so that friction and binding are reduced or eliminated, and the hook is promptly released, and the paper carriage is not retarded in its travel. Provision is also made for having the roller cam on the releasing lever normally out of the path of the carriage lugs.

Another feature of the invention consists of means for locking the hook out of use, so as to permit the use of the carriage independently of the computing mechanism when desired. For this purpose, a button is provided which has a cam to engage a part of the hook and hold the same de-

pressed out of the path of the lugs on the carriage.

This invention is also in the nature of an improvement on Wright applications Nos. 485,030, 485,046, 428,020 and 388,766.

In the accompanying drawings, Figure 1 is a rear elevation of the present improvements, showing the computing carriage hook connected to the typewriter rack, which carries the lug aforesaid; the arrow indicating the direction of letter feeding movement of the carriage. Fig. 2 is a similar view, showing the manner of releasing the hook. Fig. 3 is a plan of the devices seen at Fig. 1. Fig. 4 illustrates the manner of locking the hook out of use. Fig. 5 is a perspective view of the hook and its connection to the computing carriage. Fig. 6 is a perspective view of a hook-releasing lever. Fig. 7 shows one position of the parts in moving from the Fig. 1 position to the Fig. 2 position.

A master wheel, in the form of teeth or pins 1, projecting from a hub 2, is carried upon an arbor 3, which extends from an end plate 4 of a computing carriage. The master wheel engages internal gears 5 upon computing wheels 6, of which one is shown; said computing wheels engaging gears 7 provided upon dial wheels 8.

The computing carriage has a pin 9 engaging a slot 10 on the forward end of a lever 11 of the first order, which is fulcrumed at 12 upon the framework of the machine, and at its rear end has a slot 13 to engage a pin 14 projecting down from a block 15, in which is fixed one end of a stem 16 of a hook 17. This hook is lifted by a spring 18 (pressing up against said stem) into engagement with any of a series of lugs 19, adjustable along a rack 20, which is connected to or forms part of the paper carriage of the typewriting machine; said paper carriage driven in the direction shown by the arrow at Fig. 1, which is a rear view. As the carriage feeds along, the bottom edge of the lug 19 encounters a roll or roller cam 21 which is pivoted at 22 upon a lever 23, the latter fulcrumed at 24 upon the framework and having a stop arm 25 to engage a stop 26 also on the framework. The lug pushes the lever 23 down from the position at Fig. 7 to the position at Fig. 2, and during such movement the end of said lever bears down upon a roll or roller cam 27, piv-

- oted at 28 on the hook 17, and carries the same down out of engagement with the lug 19. The provision of these roller cams 21 and 27 makes the operation of the lever 5 and hook quick and quiet, easy and precise, obviating the screeching and jar that come with the use of steep cam faces in restricted spaces. Moreover, cams having these faces are apt to jam after a period of non-use.
- 10 They become less slippery, either by accumulation of dirt from the surrounding air, by incipient rust, or from some other cause. These objections and draw-backs I avoid in my construction.
- 15 It will be understood that the roll or roller cam 21 normally occupies the position at Fig. 1 entirely below the lugs 19, so that the paper carriage can be run along in both directions without the lugs colliding with said
- 20 roll or roller cam 21. While the hook 17 is moving from the position at Fig. 1 to the position at Fig. 7, the roll or roller cam 27 on said hook engages a cam edge 29 on the rear end of the lever 23 and raises the same, as
- 25 seen at Fig. 7. This movement is rendered very easy by the use of the roll or roller cam 27, so that the movement of the carriage is not retarded. By this means, the lever 23 is lifted sufficiently to bring the roll or roller
- 30 cam 21 into the path of the advancing lug 19, and the latter strikes the roll and depresses the lever 23, to release the hook 17, as seen at Fig. 2. Thereupon, a spring 30, connected to lever 11, returns the hook 17, lever 11, and computing carriage 4 to starting positions; or at least the spring 18 lifts said hook into engagement with the next lug 19 on the rack 20; while the lever 23 gravitates to its normal position at Fig. 1.
- 35 When it is desired to silence the hook 17, the button 31, Fig. 5, is turned, said button being fixed upon the projecting end of a short shaft 32, and a cam 33 projecting from said shaft above the stem 16 of the hook and moved by said button from the idle position at Fig. 1 to effective position at Fig. 4. A friction spring 34 forks the shaft 32 and presses against the hub of the button 31, so as to hold the latter frictionally with the
- 40 cam or pin 33 both in the effective position at Fig. 4 and in the idle position at Fig. 1.
- Variations may be resorted to within the scope of the invention, and portions of the improvements may be used without others.
- 45 Having thus described my invention, I claim:
1. The combination of a carriage lug, a computing carriage hook, a releasing lever for said hook, said lever normally out of the path of said lug, and means on said hook to engage said lever to move it into the path of said lug, to coöperate therewith, to release said hook.
- 50 2. The combination of a carriage lug, a computing carriage hook, a releaser for said

hook, said releaser normally out of the path of said lug, and means on said hook to engage said releaser to move it into the path of said lug, to coöperate therewith, to release said hook.

3. The combination of a carriage lug, a computing carriage hook, a releasing lever for said hook, said lever normally out of the path of said lug, means on said hook to engage said lever to move it into the path of said lug, to coöperate therewith to release said hook; said lever having a part to be engaged by said lug, and said hook also having a part to engage said lever, a spring tending to lift the hook into engagement with the lug, and a spring to return the hook for engagement with the succeeding lug.

4. The combination of a carriage lug, a computing carriage hook, and an interpo- 85 nent between said hook and said lug, and movable by the hook to position to engage the lug, and movable by the lug to release the hook.

5. The combination with a main carriage 90 and a computing carriage, of a hook to connect said carriages, means shiftable to position to silence said hook and lock it out of use, and means for frictionally holding said silencing means.

6. In a typewriting and computing mechanism, the combination with a type- 100 writer carriage and a lug adjustable to different locations thereon, of a computing carriage hook, a roller cam normally out of the path of said lug, and means to coöperate with said hook to move said roller cam into the path of said lug so that it may be rotated and forced aside by said lug, and also to cause said hook to be disengaged from said lug by the action of the lug upon the roller cam.

7. The combination of a carriage, a lug; a computing carriage hook, a roll, means supporting said roll normally out of the 110 path of said lug, and means on said hook to engage said supporting means and thereby shift said roll into the path of said lug to coöperate therewith to release said hook.

8. The combination of a carriage, a lug, a computing carriage hook, a roll to be engaged by said lug, an arm or lever on which said roll is mounted normally out of the path of said lug, and means dependent upon the travel of the carriage to move 120 said arm to carry said roll into the path of said lug to coöperate with the latter to release the hook therefrom.

9. The combination with a main carriage 125 and a computing carriage, of a lug on the main carriage, a computing carriage hook to engage said lug, a roll for engagement with said lug, an arm or lever whereon said roll is mounted normally out of the path of said lug, and a device on said hook to en-

gage said arm to shift said roll into the path of said lug, and thereby force the hook out of engagement with the lug.

10. The combination with a main carriage and a computing carriage, of a lug on the main carriage, a computing carriage hook to engage said lug, a roll for engagement with said lug, an arm or lever whereon said roll is mounted normally out of the path of said lug, and a roll on said hook, said arm having a part in the path of said hook-roll to shift the arm and enable the first roll to be engaged by the lug and by the coöperation of the two rolls to cause 15 the hook to become disengaged from the lug.

11. The combination with a main carriage and a computing carriage, of a lug on the main carriage, a computing carriage hook to engage said lug, a roll for engagement with said lug, an arm or lever whereon said roll is mounted normally out of the path of said lug, and a roll on said hook, said roll-carrying arm having a cam portion to be engaged by said hook-roll, to lift 20 the arm with its roll to bring the latter into the path of the lug, so that the hook-roll is under the arm at the time that the lug tends to depress the arm, whereby the hook-roll and hook are depressed, and the hook is 25 disengaged from the lug.

12. The combination with a carriage, a lug and a computing carriage hook, of a roll for engagement with said lug, a lever whereon said roll is mounted normally out 30 of the path of said lug, a roll on said hook, the lever in the path of said hook, a roll to be lifted thereby, to lift the lever roll into the path of the lug and coöperate therewith to withdraw said hook from the lug.

13. The combination of a carriage, a lug, a computing carriage hook, a roll, a lever normally supporting said roll out of the

path of said hook, means on said hook to move said lever to carry said roll into the path of said lug to coöperate therewith to 45 release the hook; said means including a roll on said hook to engage said lever; a spring tending to lift the hook into engagement with the lug, and a spring to return the hook for engagement with the succeeding lug.

14. In a typewriting and computing mechanism, the combination with a typewriter carriage and a lug adjustable to different locations thereon, of a computing carriage hook, a roll, means normally supporting said roll out of the path of said lug, and means to coöperate with said supporting means for moving said roll into the path of said lug to be engaged thereby to disengage said hook from said lug by the action of the lug upon said roll.

15. The combination with a typewriter carriage having a lug, of a computing carriage having a hook to engage said lug, and a lever mounted upon the machine frame to be called into operation by said hook during the advance of the carriage and to force 60 said hook out of engagement with the lug.

16. In a typewriting and computing mechanism, the combination with a typewriter carriage and a lug adjustable to different locations thereon, of a computing carriage hook, a cam normally out of the path of said lug, and means to coöperate with said hook to move said cam into the path of said lug to be forced aside thereby, and to cause said hook to be disengaged from said lug by the action of said lug 70 upon the cam.
